UNITED STATES PATENT OFFICE.

ALBERT J. SEAMAN, OF BOSTON, MASSACHUSETTS, ASSIGNOR TO SEAMAN ENGINE COMPANY, OF BOSTON, MASSACHUSETTS, A CORPORATION OF MASSACHUSETTS.

VALVE MECHANISM FOR INTERNAL-COMBUSTION ENGINES.

1,142,987.

Specification of Letters Patent. Patented June 15, 1915.

Application filed October 15, 1914. Serial No. 866,739.

To all whom it may concern:

Be it known that I, ALBERT J. SEAMAN, a citizen of the United States, residing at Boston, in the county of Suffolk and State of Massachusetts, have invented an Improvement in Valve Mechanism for Internal-Combustion Engines, of which the following is a specification.

This invention relates to improvements in valve-mechanism for internal combustion engines for controlling the inlet and exhaust, and is intended as an improvement upon the valve-mechanism of my application #735,378, filed December 7, 1912. The valve-mechanism of said application comprises a casing having a pair of aligned frusto-conical valve-seats having ports communicating with the engine-cylinder, a pair of hollow frusto-conical valve-bodies adapted for engagement with said seats having ports to move into register with the ports in the casing when rotated, and driving-means arranged between said valve-bodies for rotating them. In the structure shown in my said application the means employed for rotating said valve-bodies consists of intermeshing spiral gears, one of which is secured to one of the valve-bodies and the other to a positively driven shaft, and such form of driving-means, while especially well suited to the purpose, has a tendency to thrust one of the valve-bodies longitudinally with a result that one of the bodies soon too loosely fits its seat and the other too tightly fits its seat.

My present invention has for one of its objects to improve the construction of the driving-means, whereby there is no tendency to move either valve-body longitudinally, or if there is such a tendency it is equally transmitted to both valve-bodies; also in the structure of my said application the valve-bodies are connected by yielding means which permits of their longitudinal movement independently of each other and holds each body in engagement with its seat. On account of the high temperature to which these valve-bodies are subjected, said connecting-means is not as sensitive as desired and particularly so when used in connection with the particular form of driving-means there shown; and this invention has for another object the provision of an improved form of connecting-means for the

valve-bodies, whereby they are held firmly in engagement with their seats, said means having associated with it a thermal compensating-device which acts upon a rise in temperature to lengthen it, thereby admitting of expansion of the valve-bodies and casing while still firmly causing said bodies to engage their seats, the contact-pressure being maintained substantially constant and equalized.

Another object of the invention is the provision of means associated with the connecting-means for the valve-bodies for taking up the wear.

The invention has for another object the provision of an improved form of oiling-means for the valve-bodies.

Figure 1 is a central longitudinal vertical section of a valve-mechanism for internal combustion engines embodying this invention. Fig. 2 is a horizontal section of the same taken on the dotted line 2—2, Fig. 1. Fig. 3 is an end view of the same. Fig. 4 is a transverse vertical section of the same taken on the dotted line 4—4, Fig. 1. Fig. 5 is a transverse vertical section of the same taken on the dotted line 5—5, Fig. 1. Fig. 6 is an enlarged detail view of a portion of the oiling-means. Fig. 7 is a detail view of the thermal compensating-device in expanded condition.

As here shown for the purpose of illustrating one embodiment of my invention, represents a portion of an engine-cylinder having a valve-casing 12, arranged at or mounted upon its upper end. The casing 12 is provided with a pair of aligned frusto-conical recesses or valve-seats 14 and 15, arranged with their smaller ends adjacent each other and separated by a bridge-wall. Rotatably mounted in said recesses are a pair of hollow frusto-conical valve-bodies 16 and 18. These valve-bodies are open at their outer ends and are provided at their inner ends with a wall 20, having a polygonal center-hole through it. The valve-body 16 is provided with a port 36 in its side wall, which is adapted to be brought into register with a port 38, which communicates with the top of the cylinder 10. This port in the present instance may be the exhaust-port. The valve-body 18 is provided with a small port 36, which is adapted to be brought into register with a port 40,

which also communicates with the top of the cylinder 10. This port in the present instance may serve as the inlet-port. The valve-body 18 may communicate with any suitable supply of combustible to control the admission of the latter to the cylinder and the valve-body 16 may communicate with the atmosphere. A polygonal shaft 60 extends longitudinally through a hole in the bridge-wall, between the alined valve-seats, which shaft projects a short distance from each side of said wall, and its projecting end-portions enter the polygonal center-holes in the walls 20 of the valve-bodies, thereby providing for a connection of said valve-bodies with said shaft, whereby they are rotated by said shaft, and permitted to slide longitudinally thereon.

The shaft 60 has fixed to it a spiral-gear 46 which engages a spiral-gear 50, which latter gear is positively driven by any suitable means connected with the engine-shaft, not shown, so that the valve-bodies will be rotated in timed relation with the movement of the piston of the engine. The shaft 60 has arranged upon it, at each side of the spiral-gear, a collar 61, and said collars have circular peripheries and are arranged in circular recesses in the bridge-wall and serve as bearing positions for the shaft, permitting free rotation thereof in the bridge-wall, yet it will be understood that said shaft may be otherwise supported in the bridge-wall for free rotation. This form of driving-means transmits its power to both valve-bodies substantially alike, so that there is no tendency to thrust the valve-bodies longitudinally or at least no tendency to thrust one more than the other.

The valve-bodies are held in place on the shaft by means extended through said shaft, and such connecting-means is of a character whereby it is subject to automatic temperature control. As here shown, said connecting-means comprises a long bolt 70, having a head at one end and a nut with a long internally threaded shank at the other end, and said bolt is extended through the center-hole in the shaft 60, and projects therefrom at each end into or through the valve-bodies. Between the head of said bolt and the wall 20 of one of the valve-bodies washers 71 and 72 are arranged, one or more pairs being employed, as desired, and the washer or washers 71 may be composed of copper and the washer or washers 72 may be composed of steel, or in lieu thereof other materials having different ratios of expansion may be employed. The washers are made of a diameter much larger than the shaft 60, to extend over the inner face of the end wall 20 of the valve-body 16, so as to serve as a means for holding said body in place on the shaft.

The washer or washers 71 have their

sides or faces adjacent the washer or washers 72 formed with circular recesses and the edges of the recesses are beveled as shown, and the washer or washers 72 have their sides or faces adjacent the washer or washers 71 formed with beveled edges as shown, and the beveled edges of the washers 71 and 72 engage each other, but the washers 72 do not bottom in the circular recesses in the washers 71, so that there is a definite space 75 between them at such points. These washers completely fill the space between the head of the bolt and the end wall 20 of the valve-body and when at say room temperature, are in the aggregate of a predetermined thickness, but when subjected to a high temperature the washers 71 expand diametrically to a greater extent than the washers 72 and the beveled edge-portions thereof slide over the beveled edge-portions of the washers 72, as shown in Fig. 7, permitting said washers 72 to more nearly bottom in the recesses in the washers 71, and thus to reduce the aggregate distance from end to end of the set of washers and admit of a corresponding relief of the valve-body and also of the other valve-body, as will be described, permitting both valve-bodies to expand and still maintain a substantially constant contact-pressure with their valve-seats. 95

A flat washer 73 is arranged on the other end-portion of the bolt 70, which is made of a diameter large enough to extend over the inner face of the end wall 20 of the valve-body 18, and a long sleeve 74, is splined on the shank-portion of said bolt, one end of which abuts against said washer and the other end terminates in engagement with a long sleeve-like nut 75, which is screwed onto the threaded end-portion of the bolt, 105 said nut holding the sleeve 74 in firm engagement with the washer 73, and holding said washer in engagement with the end wall of the valve-body, thus clamping the several parts in assembled condition. To tightly hold said nut in engagement with the sleeve it is made automatically adjustable, and, as here shown, a torsion-spring 80 is arranged on the exterior of the shank-portion of the nut, one end of which is connected to the nut 110 and the other end is connected to the sleeve, and said spring is placed in position under tension, so that it always acts torsionally in a direction to turn the nut up tightly and thus firmly hold the parts assembled with 115 the valve-bodies in engagement with their seats with a substantial pressure, but it will be understood that said bolt is held under the control of the temperature-device, which is subject to variation in thickness due to a 120 change in temperature. This torsion-spring is employed particularly for the purpose of taking up wear, and is very desirable as the valve-bodies or their seats or both gradually wear. 125

The oiling-means here shown consists in channels 90 formed in the valve-casing, having slots by which said channels are in open communication with the valve-seats, and said channels with their slots extend from end to end of the valve-seats or thereabout, and the inner ends of said channels are in open communication with a well 91 formed in the casing, in which well the driving-gears are arranged, and the outer ends of said channels are in open communication with passages 92, extended through the casing, into which passages pipes 93 are screwed, which pipes are connected with an oil supply and pump of any suitable description, not shown, thus forming a circulatory system for the oil. Each channel 90 is preferably circular in cross-section and has arranged in it a long spiral-spring 94, one end of which is arranged to abut against a stop and the other end is engaged by a screw-plug 95, having a hole through it, arranged to engage a threaded portion of the channel, and turning of said plug acts to more or less compress the spring. The spring itself forms a tubular or cylindrical conduit for the oil and the convolutions thereof are arranged over the slot and afford a plurality of narrow spaces through which the oil passes, thus controlling the delivery of oil to and through the slot, the greater the compression of the spring the smaller the spaces and the lesser the delivery of oil. In order to obtain access to the screw-plug 95, the channel 90 is open at its outer end, which opening is closed by a screw-plug 96, and removal of said screw-plug 96, uncovers the screw-plug 95.

I claim:—

1. A valve-mechanism for internal combustion engines comprising a casing having a pair of aligned frusto-conical valve-seats arranged with their ends adjacent each other and separated by a bridge-wall and having inlet and outlet ports, a pair of hollow frusto-conical valve-bodies arranged in alignment in engagement with said seats, said valve-bodies having inlet and outlet ports, a rotatable shaft upon which both said bodies are mounted for rotation with the shaft and for axial movement on said shaft, and means to rotate said shaft, substantially as described.

2. A valve-mechanism for internal combustion engines comprising a casing having a pair of aligned frusto-conical valve-seats arranged with their ends adjacent each other and separated by a bridge-wall and having inlet and outlet ports, a pair of hollow frusto-conical valve-bodies arranged in alignment in engagement with said seats, said valve-bodies having inlet and outlet ports, a polygonal shaft having cylindrical bearing-portions arranged for rotation in said bridge-wall, upon the end-portions of which said bodies are mounted for rotation with

the shaft and for axial movement with respect to the shaft, and gearing for rotating said shaft, substantially as described.

3. A valve-mechanism for internal combustion engines comprising a casing having a pair of aligned frusto-conical valve-seats, a pair of hollow frusto-conical valve-bodies engaging said seats, means to connect said valve-bodies together whereby they are rotatable in unison, said means including a thermal compensating-device by which the connecting means is lengthened and shortened upon changes in the temperature, substantially as described.

4. A valve-mechanism for internal combustion engines comprising a casing having a pair of aligned frusto-conical valve-seats, a pair of hollow frusto-conical valve-bodies engaging said seats, and a center-bolt connecting said valve-bodies together having thereon a set of washers composed of materials of different ratios of expansion, said washers being arranged for movement with respect to each other upon changes in temperature thereby to vary their aggregate thickness, substantially as described.

5. A valve-mechanism for internal combustion engines comprising a casing having a pair of aligned frusto-conical valve-seats, a pair of hollow frusto-conical valve-bodies engaging said seats, a center-bolt connecting said valve-bodies together having arranged thereon between its head and one of the valve-bodies a set of washers composed of materials of different ratios of expansion, said washers being arranged for movement with respect to each other upon changes in temperature, thereby to vary their aggregate thickness, substantially as described.

6. A valve-mechanism for internal combustion engines comprising a casing having a pair of aligned frusto-conical valve-seats, a pair of hollow frusto-conical valve-bodies engaging said seats, and means arranged to connect said valve-bodies together whereby they are rotatable in unison, said means including a set of washers composed of materials of different ratios of expansion, some of the washers having circular recesses in their sides with beveled edges and others having beveled edges for engaging the beveled edges of the recesses of the aforesaid washers, but not bottoming in said recesses, whereby the washers are permitted to reduce in aggregate thickness upon expansion diametrically due to a rise in temperature, substantially as described.

7. A valve-mechanism for internal combustion engines comprising a casing having a pair of aligned frusto-conical valve-seats, a pair of hollow frusto-conical valve bodies engaging said seats, a center-bolt arranged to connect said valve-bodies together having a nut arranged on its threaded end-portion and a torsion-spring connected to said nut

for turning it to take up the wear, substantially as described.

8. In an internal combustion engine, the combination of a casing having aligned frusto-conical valve-seats and aligned frusto-conical bodies arranged in engagement with said seats, channels arranged in the casing communicating with each other and forming a part of a circulatory system, and having 5 slots communicating with the valve-seats, and spiral-springs arranged in said channels which cover the slots and control the delivery of oil through them to the valve-seats, substantially as described.
10. 9. In an internal combustion engine, the combination of a casing having aligned frusto-conical valve-seats and aligned frusto-conical bodies arranged in engagement with said seats, channels arranged in the casing 20 communicating with each other and forming a part of a circulatory system, and having slots communicating with the valve-seats, and spiral-springs arranged in said channels which cover the slots and control the delivery of oil through them to the valve-seats, 25 and means to compress said springs to vary the amount of oil so delivered, substantially as described.
10. In an internal combustion engine, the 30 combination of a casing having aligned frusto-conical valve seats and a well arranged between said seats, aligned frusto-conical valve-bodies arranged in engagement with said seats, means connecting said valve-

bodies together, and driving means for said valve-bodies arranged in the well, channels arranged in the casing in open communication with the well, said channels having slots by which they are in open communication with the valve-seats, said channels forming a part of a circulatory system, and springs arranged in said channels over the slots which control the delivery of oil through the slots, substantially as described.

11. A rotatable valve and a valve-seat 45 which it engages, formed in a casing, said casing having a channel with a slot communicating with the seat, and a spiral spring arranged in said channel over said slot for controlling the delivery of oil through said slot, substantially as described.

12. A rotatable valve and a valve-seat which it engages, formed in a casing, said casing having a channel with a slot communicating with the seat, and a spiral spring 55 arranged in said channel over said slot for controlling the delivery of oil through said slot, and means to vary the length of said spring and thereby to correspondingly vary the sizes of the spaces between the convolutions thereof, substantially as described.

In testimony whereof, I have signed my name to this specification, in the presence of two subscribing witnesses.

ALBERT J. SEAMAN.
